United States Patent Office.

JOSEPH BALSLEY, OF BEDFORD, INDIANA.

Letters Patent No. 98,012, dated December 21, 1869.

IMPROVED WASHING-MACHINE.

The Schedule referred to in these Letters Patent and making part of the same.

To all whom it may concern:

Be it known that I, JOSEPH BALSLEY, of Bedford, in the county of Lawrence, and State of Indiana, have invented a new and useful Improvement in Washing-Machines; and I do hereby declare that the following is a full, clear, and exact description thereof, which will enable others skilled in the art to make and use the same, reference being had to the accompanying drawings, forming part of this specification, in which—

Figure 1 is a side view of my improved machine, parts being broken away to show the construction.

Figure 2 is a top view of the same.

Figures 3 and 4 are detail views, illustrating a modified form of the spring support.

Similar letters of reference indicate corresponding parts.

My invention has for its object to improve the construction of the machine known as the "Egyptian washing-machine," so as to make it more convenient in use and more effective in operation; and

It consists in the construction and combination of various parts of the machine, as hereinafter more fully described.

A is the body of the machine, which is supported upon legs, B, of suitable length.

C is the swinging rubber, the standards D of which are rigidly attached to the round E.

The ends of the round E work in holes or sockets, in the heads or upper ends of the slides F, which pass down through holes or slots in the frame-work of the machine, or through guides attached to the body A, and the lower ends of which are securely attached to the ends of the cross-bar G, below the said body A of the machine.

H is a rope, one end of which is attached to the middle part of the cross-bar G, and which passes over a guide or pulley, I, attached to the bottom of the body A, and around the roller J, pivoted to the legs B of the machine.

The other end of the rope H is attached to the treadle K, one end of which is hinged to the bottom of the churn A, and its other end projects, so that it may be conveniently operated by the foot of the operator

to raise the rubber C, for convenience in putting in and taking out the clothes.

In the "Egyptian machine," the rubber C is forced and held down upon the clothes to give the desired pressure by the foot of the operator placed upon the treadle L, rigidly attached to the cross-bar G, said operator being thus compelled to stand upon one foot and press the treadle L down with the other foot while operating the rubber.

Operating the machine was thus very laborious and fatiguing.

In my improved machine, coiled springs, M, are placed upon the slides F, the upper ends of which springs rest against the upper part of the frame-work of the machine, or against the upper guide, through which said slides pass.

The lower ends of the springs M rest against stops adjustably attached to the slides F, so that the tension of said springs M may be increased or diminished to regulate the pressure upon the clothes.

The stops upon which the lower ends of the springs M rest, may be a pin passing through one or the other of a series of holes, formed in the slides F; or it may be an open ring-clamp, fitting upon the slides F, and provided with ears and a clamping-screw, so that it may be readily secured to the slide F when adjusted.

N is the lever or handle, by which the rubber is operated, the end of which is secured to the lower round E of the rubber standards.

The lever N is strengthened by a brace, O, the upper end of which is secured to the upper round P of the rubber standards, and the outer end of which is secured to the said lever N, as shown in figs. 1 and 2.

Having thus described my invention,

I claim as new, and desire to secure by Letters Patent—

The combination of rope H, treadle K, roller or round J, slides F, and springs M, with the roller E, handle N, and rubber standards D, when arranged and operating as shown and described.

Witnesses: JOSEPH BALSLEY.

GEREMIAH V. MATHES,
ANDREW GELWICK.
